UNITED STATES PATENT OFFICE

2,334,576

MINING APPARATUS

Charles F. Osgood, Claremont, N. H., assignor to
 Sullivan Machinery Company, a corporation of
 Massachusetts

Application July 16, 1940, Serial No. 345,702

15 Claims. (Cl. 262—28)

This invention relates to mining apparatus, and more particularly to improvements in coal mining apparatus of the combined kerf cutting and drilling type for cutting kerfs and for drilling blast holes in a coal seam.

An object of this invention is to provide an improved coal mining apparatus. Another object is to provide an improved coal mining apparatus of the combined kerf cutting and drilling type whereby blast holes may be drilled in a coal seam by drilling means associated with the kerf cutting means. Yet another object is to provide an improved coal drilling means of the type particularly adapted to use with a kerf cutting machine whereby blast holes may be drilled in the coal at points spaced from the kerf cut by the kerf cutting means. A further object is to provide an improved drilling means associated with a coal cutting machine of the top cutting type whereby blast holes may be drilled in the coal face below the cut therein and in adjacency to the mine floor. A further object is to provide an improved kerf cutting and drilling apparatus having improved means for mounting the drilling means on the coal cutting machine, whereby the drilling means may be adjusted into different drilling positions with respect to the kerf cutting means. A still further object is to provide in a coal cutting machine of the combined horizontal and shear cutter type, an improved drilling means, whereby blast holes may be drilled in the coal face at various locations with respect to the horizontal and vertical kerfs cut by the kerf cutting means. Yet another object is to provide, in a coal mining apparatus of the adjustable kerf cutter type having a kerf cutter adjustable into either horizontal bottom or top cutting positions, an improved drilling means for drilling top holes during the bottom cutting operation and for drilling bottom holes during the top cutting operation. A still further object is to provide, in a coal cutting machine of the so-called "universal" type having a rotatable cutter head for adjusting the kerf cutter into horizontal top and bottom cutting positions above and below the head axis and vertical shearing positions at either side of the head axis, an improved drilling means whereby blast holes may be drilled in the coal face at various locations in any cutting position of the kerf cutter. Still another object is to provide an improved coal drill mounted in an improved manner on a coal cutting machine, whereby the drill may be adjusted into different drilling positions about an axis coincident with the axis of rotation of the rotatable cutter head. A further object is to pro-

vide an improved means for mounting the drill on the rotatable cutter head independently of the kerf cutter, whereby the drill may be adjusted, upon rotation of the cutter head, into different drilling positions about the axis of cutter head rotation. A still further object is to provide an improved coal drill having an improved adjustable supporting structure whereby the drill may be readily adjusted into different drilling positions in an improved manner. These and other objects and advantages of the invention will, however, hereinafter more fully appear in the course of the following description and as more particularly pointed out in the appended claims.

This application is a continuation-in-part of my copending application, Serial No. 128,638, filed March 2, 1937, now matured into Patent No. 2,218,492, granted October 15, 1940.

In the accompanying drawings there are shown for purposes of illustration two forms which the invention may assume in practice.

In these drawings—

Fig. 1 is a plan view of a coal mining apparatus in which an illustrative form of the improved drilling means is incorporated.

Fig. 2 is a side elevational view of the coal mining apparatus shown in Fig. 1.

Fig. 3 is a fragmentary plan view of the forward portion of the mining apparatus shown in Fig. 1 and showing various adjusted positions of the improved drilling means.

Fig. 4 is a detail sectional view taken substantially on line 4—4 of Fig. 5.

Fig. 5 is an enlarged detail vertical sectional view taken substantially on line 5—5 of Fig. 1.

Fig. 6 is an enlarged detail sectional view taken substantially on line 6—6 of Fig. 2.

Fig. 7 is an enlarged vertical sectional view taken substantially on line 7—7 of Fig. 1.

Fig. 8 is an enlarged detail view in longitudinal vertical section taken substantially on line 8—8 of Fig. 1.

Fig. 9 is a fragmentary side elevational view of the forward portion of the mining apparatus shown in Fig. 2, illustrating a modified form of the improved drilling means.

Figs. 10 and 11 are diagrammatic views showing the coal mining apparatus in operating position in a mine entry, illustrating different adjusted positions of the improved drilling means.

In both illustrative embodiments of the improved drilling means, the same is associated with a coal cutting machine of the combined horizontal and shear cutter type commonly known as a "universal" track cutter, although it will be evi-

dent that the improved drilling means may be associated with coal cutting machines of various other types.

The coal cutting machine, in this particular instance, may be of the same general type as that disclosed in my Patent 2,007,900, patented July 9, 1935, and generally comprises a portable base 1 mounted on wheels 2 adapted to travel along a mine trackway 3 laid on the mine floor. Mounted on the base, in overlying relation thereon, is a horizontal turntable 4 journaled for rotation in an annular frame 5 adjustably supported by three screw pedestals 6 mounted on the base. Supported on the turntable and overlying the annular turntable bearing frame 5 at the forward end of the base, is a horizontal arm structure 7 on which is supported a cutter-carrying-head 8 rotatable about a horizontal axis extending longitudinally of the arm structure 7. Supported by the rotatable cutter-carrying-head 8 is a transverse guiding frame 9, in which is slidably guided a supporting frame 10, and pivotally mounted on this supporting frame for swinging movement about an axis at right angles to the head axis is a plane kerf cutter 11. This kerf cutter is in the form of a narrow elongated plane cutter bar 12 having guided for circulation about its margin an endless cutter chain 13. As shown in Fig. 8, the rotatable cutter-carrying-head 8 has an annular neck bearing portion 14 journaled for rotation in a bearing frame 15 supported by the arm structure 7. As fully described in the Patent No. 2,007,900 above referred to supported by the turntable 4 is a motor 16 having its power shaft connected through transmission gearing, including a horizontal shaft 17 journaled within the arm structure 7, a transmission shaft 18 and intermeshing spur gearing 19, for connecting the shafts 17 and 18 in driving relation, and the shaft 18 is operatively connected to the cutter chain for driving the latter, and the shaft 17 drives gearing comprising an internal gear 20 secured to the annular bearing frame 15, for rotating the cutter head. Also driven through the transmission shaft 18 is the mechanism for adjusting the sliding frame 10 along its guiding frame 9 relative to the cutter head frame for adjusting the kerf cutter into parallel cutting planes toward and from the head axis. Supported on the truck frame is a motor 21 having its power shaft connected through transmission mechanism arranged within a transmission housing 22 for driving the truck wheels to propel the apparatus along the mine trackway and for adjusting the screw pedestals 6 for effecting vertical adjustment and universal tilting of the turntable 4 with respect to the portable base. As fully described in the Patent No. 2,007,900 mentioned above, this coal mining apparatus is capable of cutting horizontal kerfs at the floor and roof levels and horizontal kerfs at any intermediate level, and parallel vertical shear kerfs at either side of the head axis; and in any adjusted position of the kerf cutter, the apparatus may be operated to sump the kerf cutter within the coal seam, swing the kerf cutter arcuately in its plane and to withdraw the kerf cutter from the coal seam in accordance with the well known arcwll method of cutting. As the specific structure of the coal mining apparatus does not enter into this invention, other than the particular cooperation thereof with the drilling means, and is fully described in the above mentioned Patent No. 2,007,900, further

detailed description thereof is herein unnecessary.

Now referring to the illustrative embodiment of the improved drilling means shown in Figs. 1 to 7, inclusive, it will be noted that the drilling means, generally designated 25, is supported by the rotatable cutter head 8 at the side of the latter opposite from the cutter bar and wholly independently of the cutter bar, so that when the cutter bar is in top cutting position the drilling means is supported beneath the cutter head and when the cutter bar is in bottom cutting position the cutter bar is supported above the cutter head. Mounted for rotation on the cutter head frame, about an axis aligned with the pivotal axis of the cutter bar 12, is a turntable 26, a frame 27 secured to the head frame providing a journal for the turntable. The turntable may be locked in its adjusted position to the frame 27 and cutter head in any suitable manner, such as by a locking screw 28 provided with an operating handle 29 and engageable with the turntable. Swivelled at 30 on the turntable 26, on an axis at right angles to the turntable axis, is a support 31 carrying an elongated arm 32 on which the drilling means, generally designated 25, is mounted in a manner to be later described. The swivelled support 31 may be locked in its adjusted position relative to the turntable 26 by a clamping means, generally designated 33, shown in Figs. 4 and 5, and the drilling means may be clamped to a support 34 at the outer extremity of the arm 32 by similar clamping means, generally designated 35. As shown in Figs. 4 and 5, the turntable 26 has an upstanding projection 36, and keyed to this projection is a shaft 37 arranged with its axis coincident with the pivotal axis 30. The support 31 has spaced projections 38 journaled at 39 on the shaft 37 so that the arm may be swung about its pivotal mounting on the turntable into different angularly related positions with respect thereto. The arm support 31 may be locked in adjusted position by a clamp member 40 splined to the shaft 37 and having its inner surface serrated for engagement with the serrated outer surface of a plate 41 secured to the turntable projection 36. Secured to the threaded reduced end 42 of the shaft is a nut 43 having an operating handle 44 for pressing the plates together to effect locking. As previously mentioned, the clamping means 35 is similar to the clamping means 33 and is adapted to lock the drilling means 25 in its different adjusted positions about its pivotal axis 45 relative to the support 34 on the arm 32. The clamping means 35 comprises, as shown in Fig. 6, friction locking plates 46 interposed between the opposite faces of a bearing lug 47 by which the drilling means is supported, and passing through apertures in bearing lugs 48 on the support 34 and the locking plates, is a shaft 49 keyed to one of the bearing lugs 48 and having a threaded end 50 on which is threaded an adjusting nut 51 provided with an operating handle 52. When the nut 51 is tightened, the plates are pressed together frictionally to hold the parts in adjusted position. The plates, if desired, may be serrated to provide for firm holding of the parts. The bearing lug 47 is integral with a support 53 on which drilling means is mounted, and this support is swivelled at 54 on the shaft 49. The drilling-means-support 53 provides a circular bearing recess 55 in which is rotatably mounted an annular bearing flange 56 on a casing 57 of the drilling means. The

flange 56 is retained within the bearing recess by means of an annular retaining ring 58 secured to the swivelled support 53. Any suitable locking means may be employed for locking the swivelled drill casing 57 to the support 53, such as a clamping screw 59 having an operating handle 60 and engaging the serrated outer surface 61 of the annular bearing flange 56.

The coal drilling means 25 may be of any conventional and well known design and, in this instance, comprises a motor 62 supported by the drill casing 51 and having its power shaft coupled to a drive shaft 63 suitably journaled within the drill casing. Keyed to the shaft 63 are spur gears 64 and 65 of different tooth ratio meshing with gears 66 and 67 respectively. The gears 66 and 67 are connected in driving relation with the drill feeding and rotation mechanism under the control of friction clutches, in the same general manner as that disclosed in the Holmes Patent 1,903,658, patented April 11, 1933. The drill rotating and feeding stem 68 carries a chuck 69 for receiving the shank of a usual auger drill steel 10 (see Fig. 6). When both clutches of the drill feeding and rotation mechanism are applied, the drill steel may be fed forwardly at a slow drilling speed, and when one or the other of the clutches is released, the drill steel may be fed either forwardly or rearwardly at a relatively high positioning speed.

In the form of the invention shown in Fig. 9, the drill supporting structure and drilling means are essentially the same as those above described with the exception that extensible power devices are provided for adjusting the arm and drill support about their respective pivotal axes. These power devices preferably comprise hydraulic cylinder and piston devices 71 and 72 to which liquid under pressure may be supplied from any suitable source. The cylinder and piston device 71 has its cylinder pivotally connected at 73 to the support 31 and its piston rod 74 pivotally connected at 75 to the swivel support 53. The cylinder and piston device 72 has its cylinder pivotally mounted at 76 on the turntable 26 and its piston rod 77 pivotally connected at 78 to the outer end of the arm 32. By operating these cylinder and piston devices 71 and 72, the arm and drill support may be swung into different adjusted positions about their respective pivotal axes, and when the liquid is trapped within the cylinders the parts are locked in their adjusted positions. The provision of the power adjusting devices for effecting adjustment of the drilling means eliminates the necessity of manipulation of the relatively heavy drill parts, thereby aiding in the setting up of the drill. Otherwise this form of the invention is the same as that above described.

The mode of operation of the improved mining apparatus will be clearly apparent from the description given. The drilling means may be transported about the mine from one working place to another while the drill is resting on the top of the turntable or in any other convenient position. When the working place is reached, the cutter-carrying-head 8 of the coal machine may be adjusted into position on the cutter bar 12 in any desired horizontal or vertical cutting planes between the mine roof and mine floor and between the ribs of the entry, and the cutter bar may be swiped in, swung arcuately about its plane and withdrawn from the coal seam in accordance with the arcwall method of cutting, in the manner well known to those skilled in the art.

When it is desired to cut a horizontal kerf at or near the level of the mine floor, the cutter head 8 may be disposed in the position shown in Fig. 2 and the bar adjusting mechanism may be operated to adjust the sliding frame 10 downwardly along the guiding frame 9 to lower the cutter bar into its bottom cutting position. During bottom cutting, the drill is disposed in the position shown in Fig. 10 above the cutter head and may be adjusted to drill top holes in the coal face at any desired location at or near the roof level and in the ribs. When it is desired to cut a horizontal kerf at or near the roof level, the cutter head 8 of the coal cutting machine may be rotated about its axis to locate the cutter bar in horizontal top cutting position above the axis of head rotation. During top cutting, the drill is disposed beneath the cutter head, as shown in Fig. 11, and may be adjusted to drill bottom holes in the coal face at any desired location at or near the floor level and in the ribs. If desired, the screw pedestals 6 of the turntable supporting means of the coal cutting machine may be adjusted to elevate the turntable to provide more space beneath the cutter head, thereby to facilitate adjustment of the drill supporting structure during bottom hole drilling. By the provision of the swivelled supporting structure for the drill, the latter may be adjusted into positions to drill blast holes in the coal face at different inclinations or in parallelism at different locations and in either rib, and when the cutter head is turned into shear cutting position, holes may be drilled in the coal face at any desired point at either side of the vertical kerf, at or near the roof level or at or near the floor level.

As a result of this invention, it will be noted that an improved coal mining apparatus of the combined kerf cutting and drilling type is provided for cutting kerfs and drilling blast holes at any desired location in the coal seam. It will further be evident that an improved coal mining apparatus of the combined kerf cutting and drilling type is provided, having drilling means mounted on the coal cutting machine, whereby blast holes may be drilled in the coal face at points spaced from the kerf cut by the kerf cutting means. It will still further be evident that by the provision of the improved adjustable supporting structure for the drill and the improved manner of mounting the drill on the rotatable cutter head of the coal cutting machine, it is possible quickly to adjust the drill to drill holes at any desired location in the coal face and in either rib of the mine entry. Other uses and advantages of the improved coal mining apparatus will be clearly apparent to those skilled in the art.

While there are in this application specifically described two forms which the invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a mining apparatus, in combination, a coal cutting machine having a horizontal kerf cutter for cutting plane kerfs in a coal face and means for adjusting said kerf cutter into a bottom cutting position to cut a kerf near the floor of a mine and into a top cutting position for cut-

ting a kerf near the mine roof, said cutter adjusting means including a cutter supporting and adjusting element mounted at the front end of the machine in adjacency to the rearward end of said kerf cutter and adjustable to position said kerf cutter as aforesaid, a coal drill, and a supporting structure for said drill mounted on said supporting and adjusting element for supporting said drill wholly independently of said kerf cutter, said supporting structure being adjustable concurrently with said supporting and adjusting element during adjustment of said kerf cutter as aforesaid to position said drill above the plane of said kerf cutter when the latter is in its bottom cutting position and to position said drill below the plane of said kerf cutter when the latter is in its top cutting position, said coal drill in either of aforesaid supported positions being adapted to drill horizontal blast holes in the coal face.

2. In a mining apparatus, in combination, a coal cutting machine having a cutter head rotatable about a horizontal axis and carrying a kerf cutter for rotation therewith about the axis of head rotation into different cutting planes for cutting kerfs at different locations in a coal face, a coal drill, and means for mounting said drill on said rotatable cutter head independently of any support by said kerf cutter, said drill mounting means supporting said drill on said cutter head for concurrent adjustment therewith about the axis of head rotation into different drilling positions to enable said drill to drill blast holes in the coal face cut by said kerf cutter.

3. In a mining apparatus, in combination, a coal cutting machine having a kerf cutter for cutting kerfs in a coal seam and supporting means for said kerf cutter adjustable to locate said kerf cutter in a horizontal top cutting position and in a horizontal bottom cutting position, said adjustable supporting means including a supporting and adjusting element for adjusting said kerf cutter into aforesaid positions, a coal drill for drilling blast holes in the coal seam, and supporting means for mounting said drill on said supporting and adjusting element for concurrent adjustment therewith during adjustment of said kerf cutter, said supporting means being mounted on said supporting and adjusting element wholly independently of said kerf cutter and adjustable therewith while at all times supported thereby into a bottom drilling position below said kerf cutter when the latter is in its top cutting position and into a top drilling position above said kerf cutter when the latter is in its bottom cutting position.

4. In a mining apparatus, the combination with a coal cutting machine comprising a rotatable cutter head carrying a kerf cutter, said kerf cutter rotatable with said cutter head about the head axis into different cutting planes, of a coal drill, and an adjustable supporting structure mounted on said rotatable cutter head for supporting said coal drill independently of said kerf cutter, said supporting structure adjustable with said cutter head about the head axis and said supporting structure supporting said coal drill for adjustment concurrently with said cutter head relative to the cutting machine through a wide range of drilling positions for drilling holes at different locations in the coal face cut by said kerf cutter, said supporting structure including elements for supporting said coal drill and through which the drill is connected to the cutter head of the cutting machine during adjustment thereof into any of its drilling positions.

5. In a mining apparatus, the combination with a coal cutting machine having a rotatable cutter head carrying a kerf cutter and rotatable to adjust said kerf cutter into different cutting planes about the head axis, of a coal drill, and an adjustable supporting structure permanently mounted on said cutter head for supporting said coal drill independently of the kerf cutter, said supporting structure supporting said coal drill for concurrent swiveled adjustment with the cutter head about the axis of head rotation into horizontal drilling positions above and below and at either side of the cutter head axis to drill horizontal holes in the coal face near the mine roof and near the mine floor and at either side of the cutting machine, said supporting structure including elements for supporting said coal drill in any of its adjusted positions and through which the drill is always connected to the cutter head of the cutting machine during adjustment thereof into all of aforesaid adjusted positions, said supporting elements being mounted on said cutter head to rotate therewith to effect bodily adjustment of said drill in an arcuate path about said head axis.
6. In a mining apparatus, the combination with a coal cutting machine comprising a support swingable horizontally about a vertical axis and a rotatable cutter head mounted on said horizontally swingable support and carrying a kerf cutter, said cutter head rotatable relative to said support to adjust said kerf cutter into different cutting planes about the axis of head rotation, of a coal drill, and an adjustable supporting structure mounted on said cutter head in advance of said horizontally swingable support for supporting said coal drill on said cutter head independently of said kerf cutter, said supporting structure supporting said coal drill for adjustment with said cutter head about the axis of head rotation into horizontal drilling positions above and below and at either side of the cutter head axis, said supporting structure including relatively adjustable elements for supporting said coal drill and through which said drill is always connected to the cutter head of the cutting machine during adjustment thereof into any of aforesaid drilling positions, said elements mounted on said cutter head to rotate with said head about said head axis to move said drill in an arcuate path and including an element having a mounting on said cutter head adjustable to move said drill bodily to vary the radius of such path.
7. In a mining apparatus, the combination with a coal cutting machine having a rotatable cutter head carrying a pivoted kerf cutter, of a coal drill, and an adjustable supporting structure for said coal drill mounted on said cutter head independently of said kerf cutter and relative to which the latter is swingable, said supporting structure supporting said coal drill for adjustment concurrently with said cutter head about the axis of head rotation into horizontal drilling positions above and below and at either side of said head axis, and said supporting structure including a drill supporting element pivotally mounted on said cutter head to swing relative thereto and by which said coal drill is carried in all the various positions of adjustment thereof.
8. In a mining apparatus, the combination with a coal cutting machine having a rotatable cutter head carrying a pivoted kerf cutter, of a coal drill, and an adjustable supporting structure for said coal drill mounted on said cutter head independently of said kerf cutter and relative to which

the latter is swingable, said supporting structure supporting said coal drill for adjustment concurrently with said cutter head about the axis of head rotation into horizontal drilling positions above and below and at either side of said head axis, and said supporting structure including a drill supporting element pivotally mounted on said cutter head to swing relative thereto about an axis in the same straight line with the pivot of said kerf cutter and by which said coal drill is carried in all the various positions of adjustment thereof.

9. In a mining apparatus, the combination with a coal cutting machine having a rotatable cutter head carrying a pivoted kerf cutter, of a coal drill, and an adjustable supporting structure for said coal drill mounted on said cutter head independently of said kerf cutter and relative to which the latter is swingable, said supporting structure supporting said coal drill for adjustment with said cutter head about the axis of head rotation into horizontal drilling positions above and below and at either side of said head axis, and said supporting structure including elements one of which is a drill supporting element pivotally mounted on said cutter head to swing relative thereto, and extensible power devices for adjusting elements of said supporting structure and for locking said supporting structure in its adjusted position.

10. In a mining apparatus, the combination with a coal cutting machine having a rotatable cutter head carrying a pivoted kerf cutter, of a coal drill, and an adjustable supporting structure for said coal drill mounted on said cutter head independently of said kerf cutter and relative to which the latter is swingable, said supporting structure supporting said coal drill for adjustment with said cutter head about the axis of head rotation into horizontal drilling positions above and below and at either side of said head axis, and said supporting structure including elements one of which is a drill supporting element pivotally mounted on said cutter head to swing relative thereto about an axis coincident with the pivot of said kerf cutter, and extensible power devices for adjusting elements of said supporting structure and for locking said supporting structure in its adjusted position.

11. In a mining apparatus, the combination with a coal cutting machine having a rotatable cutter head carrying a pivoted kerf cutter, of a coal drill, and an adjustable supporting structure for said coal drill mounted on said cutter head independently of said kerf cutter and relative to which the latter is swingable, said supporting structure supporting said coal drill for adjustment with said cutter head about the axis of head rotation into horizontal drilling positions above and below and at either side of said head axis, and said supporting structure including elements one of which is a drill supporting element pivotally mounted on said cutter head to swing relative thereto about an axis coincident with the pivot of said kerf cutter, and extensible power devices for adjusting elements of said supporting structure and for locking said supporting structure in its adjusted position, said power devices comprising hydraulic cylinders containing reciprocable pistons.

12. In a mining apparatus, in combination, a portable base, a cutter head mounted on said base to rotate relative thereto about a horizontal axis, a kerf cutter pivotally mounted on said cutter head to swing relative thereto and adjustable with said head about the head axis into horizontal

cutting positions above and below said cutter head, a coal drill, and means for mounting said drill on said cutter head wholly independently of said kerf cutter at the side of said cutter head opposite from said kerf cutter, said drill mounting means being concurrently adjustable with said cutter head about the head axis during kerf cutter adjustment while wholly supported by said head, said mounting means being adjustable into positions to support said drill on said cutter head to drill holes above said cutter head when said kerf cutter is positioned below said cutter head and to drill holes below said cutter head when said kerf cutter is positioned above said cutter head.

13. In a mining apparatus, in combination, a portable base, a cutter head mounted on said base to rotate relative thereto about a horizontal axis, a kerf cutter pivotally mounted on said cutter head to swing relative thereto and adjustable with said head about the head axis into horizontal cutting positions above and below said cutter head, a coal drill, and means for mounting said drill on said cutter head wholly independently of said kerf cutter at the side of said cutter head opposite from said kerf cutter, said drill mounting means being concurrently adjustable with said cutter head about the head axis during kerf cutter adjustment while wholly supported by said head, said mounting means being adjustable into positions to support said drill on said cutter head to drill holes above said cutter head when said kerf cutter is positioned below said cutter head and to drill holes below said cutter head when said kerf cutter is positioned above said cutter head, said drill mounting means including drill supporting means adjustable horizontally relative to said cutter head while supported by the latter and while said kerf cutter remains stationary as regards swinging movement about its pivot relative to said cutter head.

14. In a mining apparatus, in combination, a portable base, a cutter head mounted on said base to rotate relative thereto about a horizontal axis, a kerf cutter pivotally mounted on said cutter head to swing relative thereto and adjustable with said head about the head axis into horizontal cutting positions above and below said cutter head, a coal drill, and means for mounting said drill on said cutter head wholly independently of said kerf cutter at the side of said cutter head opposite from said kerf cutter, said drill mounting means being concurrently adjustable with said cutter head about the head axis during kerf cutter adjustment while wholly supported by said head, said mounting means being adjustable into positions to support said drill on said cutter head to drill holes above said cutter head when said kerf cutter is positioned below said cutter head and to drill holes below said cutter head when said kerf cutter is positioned above said cutter head, said drill mounting means including drill supporting means adjustable vertically relative to said cutter head while supported by the latter and while said kerf cutter remains stationary as regards swinging movement about its pivot relative to said cutter head.

15. In a mining apparatus, in combination, a portable base, a cutter head mounted on said base to rotate relative thereto about a horizontal axis, a kerf cutter pivotally mounted on said cutter head to swing relative thereto and adjustable with said head about the head axis into horizontal cutting positions above and below said cutter head, a coal drill, and means for mounting said drill on said cutter head wholly independently of said kerf

cutter at the side of said cutter head opposite from said kerf cutter, said drill mounting means being concurrently adjustable with said cutter head about the head axis during kerf cutter adjustment while wholly supported by said head, said mounting means being adjustable into positions to support said drill on said cutter head to drill holes above said cutter head when said kerf cutter is positioned below said cutter head and to

drill holes below said cutter head when said kerf cutter is positioned above said cutter head, said drill mounting means including drill supporting means adjustable horizontally and vertically relative to said cutter head while supported by the latter and while said kerf cutter remains stationary as regards swinging movement about its pivot relative to said cutter head.

CHARLES F. OSGOOD.
